Application May 5, 1948, Serial No. 25,174

7 Claims. (Cl. 13—34)

1

The use of vertical studs or rods for supporting and supplying electric current to continuous electrodes has previously been suggested in United States Patent No. 2,224,739 to Manfredini. The present invention relates to improvements upon the inventions of that earlier patent.

In the operation of a continuous electrode such as is employed in the production of aluminum, the bottom portion of the electrode reaches a temperature above about 750° and on the surface approaches the temperature of the bath or about 950° C. At the top, the electrode will have a temperature in the order of from 135° C. to 250° C. As the electrode is consumed, additional quantities of electrode paste are added. This paste is made up of mixtures of carbonaceous material such as ground-up coke and a binder of a bituminous nature. As is well known in this art, the binder ordinarily employed in making the paste has a melting point above normal temperature but substantially below the temperature of 135° C. so that the so-called paste is substantially solid at normal temperatures but readily melts at the temperature near the top of the electrode. The heat of the mass keeps the paste in a molten state until very gradually and over the course of many days the binder is volatilized sufficiently so that the pasty mass first becomes sufficiently solid not to flow and finally becomes thoroughly coked.

In the Manfredini structure, tapered rods extend down from the top into the mass. Manfredini recommends that these be arranged in three rows or tiers. The lowest may, at its low point, go down within about 20 cm. of the bottom of the electrode, the second is about 20 cm. higher and the third is again 20 cm. above the second. Thus when the lowest one is reinserted after being drawn out and cooled, it will be about 80 cm. from the bottom of the electrode. The internal resistance of the mass increases toward the top, and where the mass is fluid it has substantially no conductivity. Manfredini states that his second tier of rods carries between 30% and 60% as much current as the bottom rods and states that the upper tier only projects down to the point where the mass still contains some tar. Presumably the upper rods will carry virtually no current. Manfredini also directs that the rods shall be carefully cleaned (which means that they must be cooled) before being re-introduced into the mass. Heretofore it has been considered by those experimenting with the Manfredini type of construction that it is necessary to use clean rods

and to introduce them into that portion of the mass which was still somewhat fluid in order to get a good bond between the rods and the mass which is aided by the shrinkage of the mass as the tars are volatilized.

The essential feature of Manfredini is that he uses enough contact rods so that when a rod is withdrawn and reinserted, it does not have to go down into the conductive zone but is inserted only into the zone where the paste is soft. Here the paste gradually shrinks around the rod and when it has finally hardened, the electrode forms an integral and continuous mass directly contacting the rod. To do this it was of course necessary to use considerably more rods than the minimum number necessary to carry the necessary electrical current. In fact, about twice as many.

I have discovered that the number of rods can be greatly reduced and much more efficient results can be had by working on a different theory of operation.

The change in conductivity of the electrode mass does not vary uniformly from the bottom to the top, and in order to get good conductivity, one must go down in the electrode to a point where it is very hot. The critical temperature where good conductivity is reached may vary under certain circumstances, but in any event to get satisfactory conductivity, one should go down in the mass to the point where the temperature is at least 600° C. and preferably somewhat higher. At this temperature the mass is incandescent and of course the mass at this temperature is entirely solidified and baked hard.

In accordance with my invention when a rod is withdrawn, an amount of unbaked paste is dropped into the hole insufficient to fill it above the line of incandescence, and then quickly before this paste can solidify, the rod is driven down into it. This does not give the paste a chance gradually to shrink about the rod as was formerly suggested, but apparently a substantial pressure is developed by forcing the rod into the unbaked paste which is held by the fully hardened electrode mass surrounding it. With this method of operation there are two successive contact surfaces which may cause voltage drop and so might create difficulties. One is the surface between the rod and the newly-hardened paste and the other is the surface between the solidified electrode mass and the new paste which was added. Nevertheless, I have discovered that actually the contact drop resulting from this

operation is surprisingly low and apparently is no greater than where the mass of paste is allowed slowly to shrink and harden about the rod as was formerly thought necessary.

If the operator works rapidly following my procedure it is possible to have a rod broken loose and reinserted and again carrying current in a matter of two or three minutes, which may be compared with the fact that in the previously suggested operation a newly-inserted rod would not be carrying its full load of current until it had been in the mass for about two weeks. In fact the change of rods takes so little time that I only need to supply the number of rods computed as necessary to supply the current during regular operation.

It is, of course, important that the amount of fresh paste inserted in the hole left by the withdrawn stud be carefully determined. This may be done by pouring in a predetermined amount of pre-melted paste, or a sausage-like plug of cold (and therefore solid) paste of proper size may be dropped in the hole. If the cold solid plug is employed it will of course melt quite quickly at the temperature of the bottom of the hole and will remain fluid for a reasonable length of time before it is solidified and carbonized. This latter procedure may reduce the necessary speed of action by a minute or two but in any event no undue time must be allowed to elapse before the stud is driven back into place. For example, if as much as 25 minutes is allowed to elapse between the time that the extra paste is added and the time that the stud is returned to position, virtually no bond will be obtained so almost no conductivity will result. In fact in such case it will be almost impossible to drive the stud back down to the desired level. That would mean that the hole would have to be filled with soft paste as under the old method, and then wait for many days before it could carry its electrical load. I have found that careful cleaning of the rods before re-insertion is not necessary.

Since the paste at the top of the mass is fluid when first added (that is after it heats above its melting point) precautions have to be taken to prevent an undue amount of paste from flowing down into the hole left by the withdrawn stud. One way to take care of this is to withdraw the hot stud part way so that a heated portion of the stud is adjacent the fluid paste. This can be left for a couple of hours to harden the paste around the hole so that there will be no flow. It has also been found that if a group of studs are changed in a batch and a new paste is added soon after the studs are returned, enough heat will be conducted through the studs to solidify the paste immediately around them to the point where inflow will be virtually negligible. For example, if the paste is allowed to stand for as much as three days around the studs before they are withdrawn, there is very little danger of the paste flowing into the open hole and if the studs are withdrawn on a cycle of 6 or 7 days and new paste is added shortly after the studs are re-inserted, there is no difficulty in this direction.

In the accompanying drawing I show a section through a continuous self-baking electrode of the type used for the production of aluminium, which is fitted with vertical contact rods which illustrate the method of my invention.

In these drawings, 10 designates the electrode mass. This is sectioned as a solid but it is understood that the upper part actually will be

liquid. The broken line through the mass indicates approximately the transition line where the mass is solidified. 12 indicates the fixed casing in which the electrode mass moves. The fixed casing is suspended by rods 14 from transverse beams as indicated at 16.

Current is fed to the electrode mass 10 by iron contact rods 18, each of which has a hole 19 for a pin. Four of these contact rods appear in the transverse section and it is understood that additional numbers will be in line with those indicated. For the purpose of explanation, the four rods shown are marked respectively 18a, 18b, 18c and 18d. Each of the rods 18 is bolted to a support bar 20. These bars are clamped to the bus bars 22. The bus bars 22 can be raised and lowered by the jacks 28.

When the lower end of a contact rod 18 gets down too close to the bath (say within about 10 to 20 cm.) as in the case of rod 18a, such rod has to be raised and repositioned. To do this the rod is loosened from the bus bar 22 and an appropriate tool as indicated at 30 is dropped over the end of the rod 18 gripping the pin inserted into hole 19. The tool is then twisted to loosen the rod 18 and the rod 18 is withdrawn. A small amount of paste (by which term I mean the carbonaceous material of the type from which the electrode is formed, which is pasty when warm but which in this case may be in the form of a cold, solid, sausage-like mass) is dropped into the hole left on the removal of the rod 18, but this amount of paste is insufficient to fill the hole above the incandescent level. Ordinarily it will be satisfactory if enough paste is put in the hole to raise the rod 20 or 40 cm. The rod 18 is then quickly forced firmly down into the hole, preferably while the rod is still incandescent. The paste, which has softened but is not yet baked, is squeezed up around the rod between the sides of the rod tip and the already solid, baked electrode mass and is immediately baked and hardened to grip the tip of the rod firmly and to form an almost integral mass with the previously solidified electrode.

In the drawings, the rods 18b and 18d are in the upper position and do not need to be changed. The rod 18c has just been changed and the newly-inserted electrode mass is here cross-hatched to show the space which it is occupying, though actually it will be so merged with the main mass of the electrode that electrically it will form a continuous whole. The rod 18c will be so firmly anchored into place that it can be used almost immediately to carry its share of the weight of the electrode and also to transmit electrical current to the electrode mass.

The tips of the rods 18 are preferably tapered so as to leave space within which the soft electrode mass can be squeezed between the rods and the fully baked electrode mass. These rods may, for example, have the following dimensions:

	Millimeters
Diameter at the lower end	60
Diameter at 300 mm. from the bottom	97
Diameter at 750 mm. from the bottom	100

It is understood that these figures are given only by way of illustration and to enable one to build a device of this type to the best advantage.

In the foregoing example I have shown the best method now known to me of carrying out my new method, but it is understood that the same may be modified in many particulars without departing from the spirit of my invention.

This application is a continuation in part of my earlier application Serial No. 587,513, filed April 10, 1945, which application has been abandoned and replaced by the present application.

What I claim is:

1. In the operation of an electric furnace including a self-baking continuous electrode having a bottom portion heated to a temperature in excess of 750° C. and a top portion formed of soft unbaked paste and provided with metal rods for suspending said electrode and for supplying current thereto, the method of re-positioning such rods when the wear of the bottom portion of the electrode makes it necessary to re-adjust such metal rods to a higher level which comprises: loosening a rod to be re-positioned and withdrawing it from the bottom of the hole, inserting in its hole an amount of unbaked carbonaceous paste material of a type which is molten when hot and adapted subsequently to harden by evolution and decomposition of binder ingredients and in an amount sufficient to fill the bottom of the hole for an appreciable distance but insufficient to prevent a rod from being re-inserted so that its tip will extend below the top level of incandescence of the electrode and immediately, before such paste can solidify and harden, forcing a rod firmly down into the hole with its tip below the top level of incandescence whereby soft paste is compressed between the rod and the sides of the hole and baked, and the rod is sealed in place and quickly brought into good electrical conductivity with the electrode mass.

2. A method as specified in claim 1 in which the amount of paste dropped in the hole has a volume equivalent to the capacity of the hole from the bottom up to a point between 20 cm. and 40 cm. from the bottom.

3. A method as specified in claim 1 in which the rod has a tapered tip and is forced down into the hole with sufficient force to squeeze melted paste up around the sides of the rod to seal the sides of the rod to the already solid electrode mass.

4. A method as specified in claim 1 in which the rod is reinserted in the electrode while it is still incandescent.

5. In the operation of an electric furnace including a self-baking continuous electrode provided with metal rods for suspending said electrode and supplying current thereto, the lower ends of all of these rods being normally located

in the baked bottom portion of the electrode, the method which comprises, when the wear of said baked bottom portion makes it necessary to readjust the metal rods at a higher level with respect to the mass of the electrode, loosening and fully withdrawing each of said rods from said electrode in two steps with a time interval between them, introducing a small amount of raw electrode paste into the space thus left empty in the baked bottom portion of the electrode, and driving back said rod into said space in said baked portion down to a relative level slightly above the preceding one and extending down into the zone of incandescence so as to compress said amount of raw paste between the rod and the electrode mass and thus to ensure immediate baking thereof.

6. A method as specified in claim 1 in which each rod is given a twisting movement to loosen it in the electrode before it is withdrawn.

7. A method as specified in claim 1, in which the unbaked carbonaceous paste material is added in a substantially solid form and allowed to melt in the hole and in which the rod has a tapered tip and is forced down into the hole with sufficient force to squeeze melted paste up around the sides of the rod to seal the sides of the rod to the already solid electrode mass.
